CIGAR CONTAINER

Roscoe G. Beals, De Kalb, Ill.

Application August 3, 1939, Serial No. 288,177

2 Claims. (Cl. 229—51)

This invention relates to containers, and has special reference to a container for wrapping cigars and other small articles wherein like wrapping problems are encountered.

In recent years the demand has arisen for cigar packages and packages for similar articles which are moisture tight and which are sealed over the cigar so as to prevent the escape of moisture and aroma bearing oils from the tobacco. A serious problem with this type of container is the difficulty of opening the same without damaging the cigar, particularly when the container is made of "cellophane" or similar transparent cellulosic material, and considerable loss is occasioned by the breakage of the fragile wrapper or outer surface member of the cigar in opening the package. The common expedients are in general unsatisfactory for this purpose because of the fragile nature of the cigar and the ease with which the wrapper can be broken or cracked and the article thus rendered worthless.

An object of the invention is to provide a package for cigars and the like having a novel construction arranged for opening the same.

A further object of the invention is to provide a container for cigars and the like which can be opened without exerting pressure on the contents of the article.

Other objects and advantages will appear from the following description and the accompanying drawing, in which—

Figure 1 is a perspective view of a cigar encased in my improved container;

Fig. 2 is a view showing the manner in which the container is opened;

Fig. 3 is a fragmentary section taken longitudinally through the container, the cigar being shown in outline;

Fig. 4 is a view similar to Fig. 3 showing the positions of the two portions of the package at an intermediate stage in the separation thereof, and

Fig. 5 is a view similar to Figs. 3 and 4 showing the positions of the portions of the container shortly after the separation thereof.

The invention contemplates in its preferred form the provision of a container formed of transparent sheet material of the type now commonly used for this purpose, such as "cellophane" or other processed cellulose material, and is adapted to be placed on the cigar by the usual forms of wrapping mechanism now employed for this purpose and to be sealed thereon in the usual manner, that is, either by the use of an adhesive or by the action of heat and pressure on the sheet

material, as, for example, as along the line 5 in the usual manner, it being understood that the sheet material will be of the waterproof type incorporating therein waterproofing agents which act as an adhesive to bind the parts together under the action of temperature and pressure. It will be understood, however, that the invention is not limited to this specific sheet material, but that the advantages thereof will at least in part accrue where other materials are employed.

In Figure 1 I have shown a preferred form of the invention which includes tubes 6 and 7 formed of "cellophane" or the like and adapted to receive the cigar therein, the tubes overlapping in the area 8 in a manner presently to be more fully described. The free ends of the tubes are collapsed as shown at 9 and 11 beyond the ends of the cigar and may, if desired, be overlapped as shown at 12 and 13, the overlapping portions being sealed either by a separate adhesive or by means of heat and pressure in the conventional manner. The usual band 14 may be supplied either on the outer surface of the container or may be placed on the cigar 15 within the container. When placed on the outer surface of the container it may be advantageously placed over the overlapping area 8 so as to conceal the junction between the tubes 6 and 7.

30 The tubes 6 and 7 are connected together in the area 8 to provide a joint in which the two portions can be readily severed. For this purpose the end portion 16 of the tube 7 is folded inwardly upon itself as shown in Fig. 3 in such manner that the material of the tube passes through a reversal of position at the edge 17. The end 18 of the tube 6 is received within the tube 7 and its outer surface is adhesively connected to the free surface of the fold 16 in any of the usual well known ways. In Figs. 3 to 5, inclusive, I have shown a layer 19 which is intended to designate this adhesive connection which may be a layer of adhesive or may represent an adhesive connection formed by heat and pressure applied between the fold 16 and the end portion 18. This adhesive connection is such as to completely seal the junction between the fold 16 and the end portion 18 through the complete circumference of these elements and through a relatively wide area as shown by the element 19 so as to give a substantially air and moisture-tight seal at this point.

35 The manner of opening the container is shown in Fig. 2, from which it will be seen that the user grasps the ends 9 and 11 of the container be-

yond the ends of the cigar 15 and by pulling on the ends in opposed directions longitudinally of the cigar, force is applied at the edge 17 to draw the forward edge of the fold 16 away from the tube 6, thereby causing the fold 16 to reverse its position. It will be seen that this exerts a peeling action on the adhesive, causing the fold and the end portion 18 to be drawn apart by movement of the fold laterally away from the surface of the end portion, as distinguished from applying a force longitudinally of the surface tending to cause the two sleeves to slide with respect to each other in the adhesively joined area. In Fig. 4 I have shown the positions of the parts when the seal has been partly broken, that is, at an intermediate point in the separation of the portions of the container showing the manner in which the fold 16 reverses itself during the operation, and in Fig. 5 I have shown the position of the parts just after the fold 16 has been completely reversed and at the point when the tubes have just separated. It will be seen that this operation involves no tearing or breaking of the sheet material itself, but only the opening of the seal 19 between the tubes 6 and 7. This joint construction very greatly reduces the amount of force required to separate the two surfaces, and with this arrangement a relatively slight pull on the ends of the container causes the tubes to be peeled apart, thus liberating the cigar therefrom in the manner shown in Fig. 2. It will be seen that during this operation it is entirely unnecessary for any force to be applied directly to the cigar, but instead, the force is applied solely to the container. Because of this fact there is no tendency for the opening operations to break or crack the relatively fragile wrapper forming the outer surface of the cigar, the breaking of which renders the cigar useless by destroying the draft, or in other words, al-

lowing the entrance of air into the cigar at a point other than the fired end.

The present disclosure, it will be understood, is by way of illustration and not limitation and 5 numerous alterations and changes may be made in the structure within the scope of the invention.

I claim:

1. The combination in a container for cigars 10 of an enclosure of flexible sheet material shaped to fit the cigar and having a joint intermediate the ends thereof, the sheet material on one side of the joint being folded inwardly upon itself, the inwardly folded portion being seated against the outer surface of the sheet material on the other side of the joint and adhesively secured thereto and being the sole means for connecting opposite ends of said container, the ends of the container projecting beyond the ends of the cigar 15 to be gripped to break the joint by pulling in opposite directions thereon.

2. The combination in a container for cigars 20 and the like of at least two tubular sections of flexible transparent cellulosic sheet material, 25 each closed at one end to form the ends of the container, the opposite ends of said sections overlapping in telescoping relation, the overlapping end of one of said sections being folded inwardly upon itself to form a reverse bend and bring the outer surface of the end portion of 30 said section against the outer surface of the other section, said sections being adhesively connected together solely between the outer surface of said other section and the adjacent surface of 35 said reverse bend so that when the end sections are drawn apart the inwardly folded end progressively passes through a reversal in position to break the adhesive connection.
